THERAPEUTIC CREEPING DEVICE

Reba M. Lillibridge, 9319 Canton Center Road,
Plymouth, Mich. 48170

Filed Dec. 24, 1969, Ser. No. 20,632

Term of patent 14 years

Int. Cl. D24—02

U.S. Cl. D88—5

FIG-1

FIG-2

FIG-3

FIG-4

FIG. 1 is a top plan view of a therapeutic creeping device embodying my new design;

FIG. 2 is an end elevational view as seen from the left side of FIG. 1, the other end being substantially identical;

FIG. 3 is a side elevational view, the other side being substantially identical; and

FIG. 4 is a perspective view thereof.

I claim:

The ornamental design for a therapeutic creeping device, as shown and described.
